UNITED STATES PATENT OFFICE

162,500

TARGET

Robert O. Wesley, Plymouth, Mich., assignor to
 Daisy Manufacturing Company, Plymouth,
 Mich., a corporation of Michigan

Application July 7, 1949, Serial No. 3,767

Term of patent 14 years

(Cl. D34—15)

To all whom it may concern:

Be it known that I, Robert O. Wesley, a citizen of the United States, residing in the city of Plymouth, in the county of Wayne and State of Michigan, have invented a new, original, and ornamental Design for Target, of which the following is a specification, reference being had to the accompanying drawing, forming a part hereof, wherein:

Fig. 1 is a front elevational view of the target, showing my new design;

Fig. 2 is a top plan view thereof;

Fig. 3 is a left end elevational view thereof;

Fig. 4 is a right end elevational view thereof; and

Fig. 5 is a perspective view thereof.

The dominant features of my new design are shown in solid lines in the drawing.

I claim:

The ornamental design for a target, as shown and described.

ROBERT O. WESLEY.
